UNITED STATES PATENT OFFICE.

JOHN J. BAARSON AND ANTON T. THORSON, OF ODIN, MINNESOTA.

HORSE-COLLAR.

1,144,682.

Specification of Letters Patent. Patented June 29, 1915.

Application filed May 15, 1914. Serial No. 838,792.

To all whom it may concern:

Be it known that we, JOHN J. BAARSON and ANTON T. THORSON, citizens of the United States, residing at Odin, in the county of Marten and State of Minnesota, have invented certain new and useful Improvements in Horse-Collars, of which the following is a specification.

This invention relates to pneumatic horse collars, having for one of its objects to eliminate the use of cumbersome pads, etc., used for protecting the neck and shoulders of a horse.

Another object of the invention is the peculiar manner in which the pneumatic bags are mounted in the collar so as to afford a maximum amount of elasticity and likewise preventing the displacement of the bags or the injuring of the same when undue pressure is exerted thereon.

A further object of the invention resides in the provision of protective casings for the inflating tubes of the pneumatic bags which communicates with a common opening in the collar by which the tubes are expeditiously inflated or deflated at the option of the operator, means being provided to normally close said common opening for excluding dust or other foreign materials therefrom.

Other objects as well as the nature, characteristic features and scope of our invention will be more readily understood from the following description taken in connection with the accompanying drawings and pointed out in the claims forming a part of this specification.

Referring to the drawings: Figure 1 is a longitudinal sectional view of a collar constructed in accordance with our invention, illustrating the application of the pneumatic bags, a portion of one of the latter being broken away, Fig. 2 is a side elevational view of one of the bags, Fig. 3 is a cross sectional view taken on the line 3-3 of Fig. 2, disclosing one of the pneumatic bags and its protective casing, and Fig. 4 is a sectional view taken on the line 4-4 of Fig. 1.

In the drawings wherein is illustrated the preferred embodiment of this invention, a collar generally designated 5 is provided which comprises a fore-wale 6 and after-wale 7, the former being stuffed in the usual

manner with hair, straw or the like, while the latter is provided at its upper and lower ends with filler sections 8 and 9, respectively, between each pair of which on each side of the collar is provided a pocket 10, each of the pockets having mounted therein a pneumatic bag 11, preferably made of rubber, the bags being provided with protective casings 12, made of any suitable material preferably waterproof which will prevent the perspiration of the animal from seeping through the collar and into the pneumatic tubes, thereby causing their premature discarding.

Each of the pneumatic bags 12 has extending therefrom an inflating tube 13, which extends through ways in the filler sections 9 in the bottom of the collar, each of said tubes being incased in a guard or tube 14, the latter being preferably made of metal and being engaged with guides 15, the latter being arranged approximately midway between the inner terminals of the pocket 10 and an opening 16, in the bottom of the collar with which the guards or tubes 14 communicate for permitting the expeditious inflation or deflation of the bags 12. A plate 17 preferably made of metal is mounted in the opening 16 so as to prevent the displacement of the filler sections 9, likewise providing a support for the tubes 14. In order to normally close the opening 16, a flap 17' is provided by extending a portion of the fore-wale which engages with the after-wale.

In operation, assuming that the flap 17' is in a position as shown in Fig. 1, the tube from the air pump is engaged through the guards or tubes 14 and with the tubes 13 for inflating the bags 11, the latter producing the best result when in a slightly softened condition, so as to be freely flexed when pressure is exerted thereon. When it is desired to deflate the bag 11, the valve mounted in each of the tubes 13, which may be any conventional form of valve, is opened, thereby allowing for the emission of air from the bags.

It will be understood that the above description and accompanying drawing comprehend the general and preferred embodiment of our invention and that various minor changes in details of construction, proportion and arrangement of parts may

be made within the scope of the appended claims and without sacrificing any of the advantages of our invention.

Having thus fully described our invention what we claim as new and desire to secure by Letters Patent is:

1. A horse collar including an after wale provided with oppositely disposed pockets and with an opening in the bottom, a pneumatic bag mounted in each of the pockets having the usual pump engaging tube extending therefrom, and a guard incasing each of the tubes, the guards communicating with the opening in the bottom of the collar through which access is had for inflating or deflating the bags.
2. A pneumatic horse collar provided with an opening in the bottom, including an after wale having upper and lower filler sections to provide pockets therebetween, each of the latter communicating with the opening in the bottom of the collar, a pneumatic bag mounted in each of said pockets having an inflating tube associated therewith, a casing for each of said tubes, one end of each of which communicates with said opening

for facilitating the inflation and deflation of said bags, and a flap carried by said collar for normally closing said opening.

3. A horse collar having an opening in the bottom and including a fore and after wale, the latter provided with upper and lower filler sections having pockets interposed therebetween, each of said pockets communicating with the opening in the bottom of the collar, a pneumatic bag mounted in each of the pockets and having an inflating tube extending therefrom, waterproof protective casings for said pneumatic bags, a tube incasing each of said inflating tubes and extending into said opening in the bottom of the collar for facilitating the inflation and deflation of said bags, and a flap carried by the fore wale of the collar for closing said opening.

In testimony whereof we affix our signatures in presence of two witnesses.

JOHN J. BAARSON.
ANTON T. THORSON.
